UNITED STATES PATENT OFFICE

2,269,200

METHOD OF MANUFACTURING ELASTIC FLUID TURBINE BUCKETS

Rudolph Hillner, Schenectady, N. Y., assignor to
General Electric Company, a corporation of
New York

Application January 18, 1939, Serial No. 251,587

4 Claims. (CL 29—156.8)

This invention relates to elastic fluid turbine buckets and more particularly to removable bucket units for turbines of the axial flow type and methods of manufacturing same.

In axial flow elastic fluid turbines designed for high admission pressures, for example, of the order of 1200 pounds per square inch and above, and correspondingly high initial temperatures, it is required that the buckets, particularly in the high pressure stages, be of an extremely strong and rigid construction. One form of a suitable bucket arrangement consists of a plurality of bucket units each having a base portion, a plurality of blades and a heavy cover portion all machined from a single piece of forged steel. The base of such bucket unit may be provided with a dovetail slot for removably positioning the unit onto the rotor rim. The manufacture of such bucket units from solid blocks of metal is exceedingly difficult in that accurately finished transverse passages of arcuate cross-sectional shape must be formed through the block defining the elastic fluid channels between the adjacent blade portions.

It is an object of this invention to provide a new and improved elastic fluid turbine bucket unit having a plurality of blades and base and cover portions rigidly connecting the opposite ends thereof.

It is a further object of this invention to provide a new and improved method of manufacturing elastic fluid turbine bucket units comprising a base portion, a plurality of blades and a cover portion integrally united together in a rigid unit by which method the blade portions can be manufactured with comparative ease and with great accuracy while the strength of the finished unit is such as will withstand the most extreme conditions of turbine operation.

For a consideration of what I believe to be novel and my invention, attention is directed to the following description and the claims appended thereto taken in connection with the accompanying drawings.

Referring to the drawings, Fig. 1 illustrates a suitable metal blank from which a bucket unit may be formed in accordance with my invention; Figs. 2, 3, 4, 5 and 6 are various views of the blank illustrating different steps in the manufacture of a bucket unit; Fig. 7 is a view in perspective illustrating a completed turbine bucket unit manufactured in accordance with a method of my invention.

In the machining of turbine bucket units, embodying a plurality of blades, from a single solid

block of metal or blank, considerable difficulty is experienced in accurately forming the concave and convex surfaces defining the adjacent blade walls of the unit. This difficulty is primarily due to the particular arcuate configuration of the passage which must be formed through the blank from side to side, it being of irregular shape and relatively narrow so that sufficient clearances do not exist for cutting tools of sufficient rigidity to be passed into the cavity from either side for removing metal therefrom in a satisfactory manner. In accordance with my invention, the passage defining the inner, adjacent walls of a pair of blade portions is machined out from the upper, or cover, end of the blank.

In Fig. 1 is shown a solid block of metal or blank 10 preferably of forged steel of a proper alloy which will give sufficient strength and rigidity to the finished unit for withstanding the most extreme conditions of operation when assembled in the high pressure stages of a turbine. The outer surfaces of the blank may be first rough machined or squared to some suitable preliminary shape, such as that shown. The upper end or portion, which will constitute the cover for the bucket unit, is indicated at 11; the base or lower portion in which the dovetail fastening means will be formed is indicated at 12; while the intermediate section or portion from which the blades will be formed is indicated at 13. The base portion 12 may be first slotted as indicated at 14 in Figs. 3 and 5 as a preliminary rough milling operation to the formation of the dovetail which may be completed later on in the sequence of the manufacturing steps. The rough slot 14 is useful during the immediately succeeding steps in that the positioning of the blank in the work holder of the machine is thereby facilitated. In

Fig. 2 is shown an end view of the blank having traced thereon in dotted lines a layout indicating a cross-section of a pair of blades 15 and 16 defining an arcuately shaped passage 17 therebetween which is to be milled out. Preliminary to the milling of the passage itself, a chamfered groove 18 similar in shape to the passage 17 is milled in the upper end portion 11 of the blank as shown in Fig. 3. The chamfered sides of this groove are desired for a later welding operation and also to enable an enlarged shank milling tool to be used in the machining of the passage. The passage 17 is then formed by an end milling operation illustrated in Fig. 4 in which the milling tool 19 is shown extending downwardly into the blank through the upper end thereof and

parallel with the side walls of the passage. The adjacent concave and convex walls 20 and 21 of the adjacent blade portions 15 and 16, respectively, may be formed as indicated in Fig. 5. This operation may be performed with a relatively high degree of accuracy since the milling tool 49 may be of comparatively short length and of such a diameter as to be relatively inflexible. As is well understood in the art, the adjacent surfaces of the blade portions are not truly parallel but are slightly spread apart at the upper ends so as to conform with the radius of curvature of the turbine rotor rim.

The upper end of the passage 17 is then closed by welding a suitably shaped insert 22 into the 15 chamfered groove in the upper end or cover portion 11. The welded cover portion reuniting the upper ends of the blade portions is shown more clearly in Fig. 6, the welds are V-shaped in cross section as indicated at 23. Because the welding operation is likely to set up internal stresses within the metal of the blank, it is preferred that the blank be heat treated or annealed at this stage in order that such stresses be relieved before the manufacture of the unit progresses through the succeeding stages.

The remaining steps to be performed upon the blank present no particular difficulties and may be carried out by well-known methods by anyone skilled in the art by simply machining or milling the remaining surplus of metal from the outer surfaces of the blank. The outer convex and concave sides of the blade portions 15 and 16 may be milled off leaving the cover and base portions 11 and 12 intact for separate machine operations to be performed thereon. The dovetail slot in the base portion 11 may then be completed giving it the suitable curvature for fitting onto the turbine rotor. The cover portion of the unit may be machined to the proper thickness in accordance with the degree of rigidity required for the upper ends of the blade portions. The opposite sides of the unit may be tapered in accordance with the radius of curvature of the turbine wheel and properly finished in order that adjacent bucket units will fit snugly against each other and with the proper spacing between the adjacent blades.

The finished bucket unit, as shown in Fig. 7, is of an extremely strong and rugged construction, the lower ends of the blades being integrally united with the base and being relatively immovable with respect to each other. The upper ends of the blades being integrally united through the bridging cover portion 11 further insures the complete rigidity of the blades with respect to each other, the bucket unit shown possessing substantially the same strength as regards distortion stresses as though the slot 17 extending between the adjacent blade portions had been formed therethrough from the opposite sides without disturbing the integral cover portion.

Though the bucket unit shown and described in this instance is provided with but two blades, it is obvious that the method of this invention is equally applicable in the manufacture of

bucket units having any greater number of blades. It is further understood that the dovetail type of fastening arrangement shown is merely illustrative of any suitable means for mounting the bucket units upon the turbine rotor rim.

Having described the principle of operation of my invention together with the apparatus which I now consider to represent the best embodiment thereof, I desire to have it understood that the apparatus shown is only illustrative and that the invention can be carried out by other means.

What I claim as new and desire to secure by Letters Patent of the United States is:

1. The method of making an elastic fluid turbine bucket unit from forged steel which comprises the steps of making a blank having lower intermediate and upper portions, removing material from the upper portion to form a groove tapered towards the intermediate portion and of a width and curvature near the intermediate portion substantially equal to the width and curvature of a bucket passage to be produced thereafter, removing material from the intermediate portion to define a curved bucket passage, forming a curved strip V-shaped in cross section, and fusing the strip to the walls of the groove by V-shaped welds.

2. A method of producing a turbine blade unit consisting of a plurality of blades integral with a single root, comprising providing a blank of rectangular cross-section; said blank having side, end, top, and bottom faces; forming a fluid passage in the top face thereof; said passage having its ends opening through the opposite side faces of the blank; permanently securing a shroud piece in closing relation to the open top of the passage; heat-treating the structure to remove stresses therein; and machining the blank to final form.

3. A method of producing a turbine blade unit consisting of a plurality of blades integral with a single root, comprising providing a blank of rectangular cross-section; said blank having side, end, top and bottom faces; forming a fluid passage in an end thereof; said passage having its ends opening through the opposite faces of the blank; welding a shroud piece in closing relation to the open top of the passage; heat-treating the structure to remove stresses therein; and machining the blank to final form.

4. A method of producing a turbine blade unit consisting of a plurality of blades integral with a single root, comprising providing a blank of rectangular cross-section; said blank having side, end, top and bottom faces; milling a fluid passage in an end thereof, said passage having its ends opening through the opposite faces of the blank; forming a shroud piece to fit in the open top of the passage; welding said shroud piece to the walls of the passage adjacent the upper edges of the latter; heat-treating the structure to remove stresses therein resulting from the welding; and machining the blank to final form.

RUDOLPH HILLNER.
